UNITED STATES PATENT OFFICE.

THEODOR KUNDTZ, OF CLEVELAND, OHIO.

SEWING-MACHINE TABLE OR CABINET.

SPECIFICATION forming part of Letters Patent No. 532,074, dated January 8, 1895.

Application filed June 14, 1894. Serial No. 514,510. (No model.)

To all whom it may concern:

Be it known that I, THEODOR KUNDTZ, of Cleveland, in the county of Cuyahoga and State of Ohio, have invented certain new and useful Improvements in Sewing-Machine Tables or Cabinets; and I do hereby declare the following to be a full, clear, and exact description of the invention, such as will enable others skilled in the art to which it pertains to make and use the same.

My invention relates to improvements in sewing-machine tables or cabinets and having means for lowering the head of the machine below the line of the table and means for automatically shifting the head toward and from the line of the fly-wheel of the machine in raising and lowering the head.

My present invention consists, in the improved means employed for locking the sewing-machine-head in its elevated position, whereby the unlocking of the head preparatory to lowering the same, and the locking of the head upon its elevation and actuation into the place required, relative to the line of the table, is automatically effected.

In the accompanying drawings, Figure 1 is a front side elevation of a sewing-machine-table or cabinet embodying my invention, the head of the machine being shown in position for operation. Fig. 2 is a top plan of the same, portions being broken away and in section to reduce the size of the figure and to more clearly show the construction. Fig. 3 is a front side elevation of the table or cabinet showing the sewing-machine-head in its lowered position. Fig. 4 is an elevation, partly in section, on line 4-4, Fig. 3, with the sewing-machine-head removed. Fig. 5 is a rear side elevation of the table or cabinet, showing the sewing-machine-head in its lowered position, portions being broken away to more clearly show the construction.

Referring to the drawings, A designates the sewing-machine cabinet; B, the table-top or table-proper; C, the sewing-machine-head, and B' a folding-leaf hinged, as at B², to the table-proper at the left hand side of the cabinet. The rear wall of the sewing-machine-cabinet has secured to the inner side thereof two vertically arranged bars or pieces a, (see Figs. 1 and 2) that are located a suitable dis-

tance apart and are grooved on their opposing faces, as at a'. (See Fig. 2.)

D represents a vertically-sliding-door and carrier, that is provided with tongues or tenons d engaging the aforesaid grooves a a, said sliding-door and carrier being adapted to slide up and down in grooves or ways a'. The rear wall of the cabinet is provided with an opening A' between the lower portion of bars or pieces a, and said opening is adapted to be closed by the door and carrier D, as will hereinafter more fully appear. Member D, at the top, is provided with a forwardly-extending horizontally-arranged shelf or platform, D' on which is mounted a sliding-frame E. Frame E and shelf or platform D' are tongued and grooved together, as at E', (see Fig. 4) or otherwise joined, so that the frame may move endwise upon the shelf or platform without losing its lateral alignment. The sewing-machine-head is borne by frame E.

A chain F is secured, as at F', to folding-leaf B', at or near the rear edge of the latter and a suitable distance from the axial line or hinges. Said chain leads from its points of attachment F' to and over a pulley or sheave b suitably supported from the table or cabinet and thence leads to the sliding-door and carrier D to which it is suitably secured. The attachment of member F to member D is preferably of a yielding character and consists preferably of an eye-bolt f provided with a thumb-nut f', said bolt extending through a hole d in door and carrier D, and a coil-spring f² is confined upon said bolt within hole d, a washer f³ being interposed between said spring and nut f', and member being slotted or cut away, as at d', to accommodate the manipulation of thumb-nut f'. The table-top and folding-leaf are, of course, suitably recessed or slotted to accommodate the location and operation of chain F. The arrangement and adjustment of parts are such that when leaf B' is actuated into position flush with the table-proper, as shown in Figs. 1 and 2, door and carrier D shall be elevated so as to bring the sewing-machine-head-bearing-frame E in position flush with the table-top, the latter being provided with a centrally located opening B² for the purpose of receiving said frame.

A block G is shown depending from the under side of the table-proper near the rear edge of the table. Said block, on the forward side thereof, is provided with an inclined 5 groove g. The head-bearing-frame E, at the rear, is provided with an inclined tongue or tenon e adapted to engage and operate in groove g aforesaid. The arrangement of parts is such that during the elevation of door and 10 carrier D member e enters groove g, whereby a further upward movement of the door and carrier causes frame E to be moved endwise in the direction of fly-wheel H, and the arrangement of parts being further such that 15 when the head is in its elevated or working position, the band-wheel C' thereof shall be in line with the fly-wheel, as shown in Fig. 1. In lowering door and carrier D, the motion of frame E is, of course, reversed, so that 20 the frame and head will clear the fly-wheel. The frame and head are thus shifted automatically in raising and lowering door and carrier E; and the latter is operated by folding and unfolding leaf B'. When the head 25 is lowered, in accomplishing which leaf B' is folded back over all, the leaf covers the opening in the table-top, as shown in Figs. 3 and 5. The sewing-machine cabinet is provided with doors, not shown, for closing the front 30 side of the same, and hence when the sewing-machine-head is lowered, the machine is enclosed on all sides.

I would here remark that the opening in the rear wall of the cabinet is for the purpose of 35 ventilation, in the operation of the machine.

It will be observed that member D not only performs the function of a carrier, but also serves as the door for closing the opening in the rear wall of the cabinet, the arrangement 40 of parts being such that said opening is closed by the carrier in the lower or inoperative position of the sewing-machine-head.

An important feature of my present invention consists in the mechanism employed for 45 automatically locking the sewing-machine-head in its operative position and locking said head preparatory to actuating it into its lower or inoperative position. The locking mechanism is shown to be as follows:—A horizontally-swinging latch or lever I (see Fig. 2) is fulcrumed, as at I', within a hole B³ provided in the forward part of the table-top, and said latch or lever is adapted to engage a horizontal slot K' in an upright latch-plate 50 K suitably secured to the forward edge of shelf or platform D', said slot being open at one end to accommodate the reception of the locking-latch or lever, and hole B³ in the table-top being sufficiently large to accommodate

the operation of said latch or lever. Latch 60 or lever I is operatively connected with a rod or bar L that extends outwardly and terminates in suitable proximity to the axial line of folding-leaf B', the table-top being provided with a hole B⁴ to accommodate the location 65 and operation of said rod or bar. The arrangement of parts is such that rod or bar L, in its normal position, when leaf B' is folded over the sewing-machine-head, shall, at its outer end, protrude outside of the table-top, 70 as shown at L' in Fig. 3, into position to be engaged by the folding-leaf when the latter is actuated into position flush with the table-top as required to elevate the sewing-machine-head into an operative position. 75

Suitable means are provided for retaining rod or bar L, and consequently the locking-latch or lever, in their normal or inoperative position, and this means consists preferably of a leaf-spring M that is suitably supported 80 within the table top and acts in the direction to retain the locking-latch or lever in its unlocking or inoperative position, said spring being engaged and adapted to be placed under tension, in actuating the locking-latch or 85 lever into an operative position, by a lug or projection L² on rod or bar L, and hole B⁴ in the table-top is enlarged, as at B⁵, to accommodate the location and operation of said spring and to form suitable bearing, as at M', 90 for the ends of the spring.

What I claim is—

In combination, a sewing-machine-table or cabinet having a reciprocating-carrier D and folding-leaf B' operatively connected with the 95 carrier, a shelf or platform D' rigid with the carrier and designed to bear the sewing-machine-head, latch-plate K fixed to said shelf or platform and provided with a slot K', swinging-latch I in the table-top, rod or bar 100 L operatively connected with said latch and adapted to be operatively engaged by the aforesaid folding-leaf, said bar or rod having a lug or projection L², a spring M engaging the aforesaid lug or projection on the 105 latch-actuating bar or rod and the table-top being chambered to accommodate the location and operation of said spring and locking-mechanism, the arrangement of parts being substantially as shown, for the purpose specified. 110

In testimony whereof I sign this specification, in the presence of two witnesses, this 9th day of June, 1894.

THEODOR KUNDTZ.
